UNITED STATES PATENT OFFICE

JOHN M. VAN HEUSEN, OF JAMAICA PLAIN, MASSACHUSETTS.

RUBBER HEEL.

1,140,635.

Specification of Letters Patent. Patented May 25, 1915.

Application filed March 5, 1915. Serial No. 12,257.

To all whom it may concern:

Be it known that I, JOHN M. VAN HEUSEN, a citizen of the United States, residing at No. 101 Robinwood avenue, Jamaica Plain, Massachusetts, have invented certain new and useful Improvements in Rubber Heels; and I do hereby declare the following to be a full, clear, and exact description of the invention, such as will enable others skilled in the art to which it appertains to make and use the same.

The many advantages of the rubber heel have been so fully established and elaborately explained and developed that it is no longer necessary, in the present state of the art, to look upon them as in any sense open to contention. Nevertheless, in spite of their benefit and utility, it is undeniable that the extent of their use is proportionately very small as compared with the ordinary leather heel and great difficulty is encountered in materially increasing the number of users.

The main objection to the use of the rubber-heel and one which has been sufficient in the great majority of cases to prevent its acceptance lies in the fact that it gives to the wearer the sensation that he is walking with a stealthy or feline tread, which is alike unpleasant and disagreeable to himself and startling and otherwise obnoxious to others; in sharp contrast to the natural desire, both on the part of the wearer and on the part of others, that his presence and approach be manifested in a decided and plainly audible manner as in the customary intercourse of men.

The purpose of the present invention is to preserve the structural advantages of the rubber heel, and yet to deprive it of its furtive, muffled and surreptitious characteristics, so that there shall be nothing connected with its use which would suggest an unannounced, sly, covert or skulking approach. To this end, as will hereinafter more fully appear, I provide the rubber heel with an adjunct which will deprive it of its cat's-paw effect, while still preserving the cushioning action which is the foundation of its utility. At the same time, the construction has neither the purpose nor effect of the well known "wear-plates" heretofore proposed for protecting heels of rubber and of leather from excessive wear, and, in fact, is differentiated therefrom by reason of the circumstance that the tread

element of my insert is of such a metal and of such a tread area that it will wear away in substantial coincidence with the adjacent rubber, as will hereinafter more fully appear.

In the accompanying drawing, Figure 1 represents a bottom plan view, partly in section, of a rubber heel embodying the fundamental characteristic features of the invention, the heel shown in Fig. 1 being intended for use on the left shoe of the wearer; Fig. 2 represents a bottom plan view, the heel therein shown being intended for use on the right shoe of the wearer; Fig. 3 represents, in side elevation, and partial section, the heel portion of a boot or shoe provided with a rubber heel made in accordance with my invention; Fig. 4 represents a sectional view on a plan indicated by the line 4-4 of Fig. 1; and Fig. 5 represents a perspective view of the adjunct hereinbefore referred to.

Similar letters of reference indicate similar parts throughout the several views.

Referring to the drawing, A indicates the heel portion of a boot or shoe to which is attached, in any usual or convenient manner the leather heel *a* provided with the resilient heel section *b*. The rubber heel section *b* may be applied to the leather heel section *a* in any usual or preferred manner, familiar to the art, as, for instance, by the countersunk nails *c* provided with metal washers *d*, so as to make up a reliable structure consisting of a leather base with a subjacent tread portion of rubber of the desired elasticity established by practice as suitable for realizing the advantages of cushioning the tread of the heel of the wearer. Together with these main elements of the structure, I make use, for the purposes of the invention, of the adjunct hereinbefore referred to.

As shown in the drawing, this adjunct consists of a metal insert, of such a character that it will present an edge *e* flush with the bottom plane of the heel, and at the location which observation has shown to be the one which, in the great majority of cases, first comes in contact with the pavement, floor, or other surface upon which the wearer is walking. In the form shown, this is accomplished by making the adjunct of a piece of steel cast or bent to present the edge *e* referred to and slightly inclined therefrom (as indicated more fully in Fig. 4) to join a main body portion *f*, which may

be provided with an enlargement *g* having a nail hole *h*.

- The adjunct may be vulcanized in place and may rely for its permanence simply upon the vulcanization, or it may be further secured against accidental displacement by driving a nail through the hole *h*, as indicated in Fig. 3. It will be understood, however, that when the nail is employed, it shall not interfere with the freedom of movement of the plate or adjunct, for the reason that the adjunct is intended to be so related to the rubber heel as a whole that it will yield freely to the weight of the wearer and will not interfere with the normal function of the rubber heel, that is to say, the function of the wearer. At the same time, it is itself protected from excessive wearing by reason of its free yield, and nevertheless possesses all of the advantages which it is the purpose of the invention to provide, including particularly and fundamentally, the advantage of announcing the approach of the wearer in a manner practically indistinguishable from that of the usual leather heeled shoe. In the embodiment of the invention illustrated, these combined effects are obtained by so mounting the metallic insert or adjunct that its tread portion will be supported by a large body of rubber which is freely resilient and which is compressed in the usual manner by the wearer, as he walks. In order to render this feasible, the metallic insert occupies a position about midway of the thickness of the rubber heel and the upturned end of the insert terminates in the edge *e* hereinbefore referred to. A sufficient rocking motion of the metallic insert is thereby provided as the wearer puts his heel upon the ground, to give the desired yield, to protect the tread portion from excessive wear, to permit it to wear nevertheless

evenly with the rubber, while, at the same time giving the desired audible announcement of the wearer's approach.

The insert, as above indicated, is preferably made of steel, or of like or similar material, designed to give a distinctly audible sound in walking and which is nevertheless adapted to wear away with a uniformity substantially equal to that of the rubber itself, having in mind the location of the edge portion of the insert, so that the heel and insert will, so far as possible, maintain a practically uniform level of wear. As hereinbefore noted, the yield of the insert materially contributes to this desired uniformity of wear, in addition to the function of not interfering substantially with the cushioning effect of the rubber heel as an entirety.

What I claim is:

A rubber heel provided at its outer edge, at that portion which first touches the ground in the act of walking, with a metallic tread element whose tread surface is flush with the bottom of the heel and which is provided with an anchoring portion embedded within the rubber body of the heel and yieldingly supported therein by the cushioning effect of the rubber, the tread element being of such a metal and having such a tread area that it will wear away in substantial coincidence with the adjacent rubber, and, in walking, will give an audible click closely simulating the noise made by a leather heel; substantially as described.

In testimony whereof I affix my signature, in presence of two witnesses.

JOHN M. VAN HEUSEN.

Witnesses:

IDA C. KRAY,
NELSON B. TODD.

Copies of this patent may be obtained for five cents each, by addressing the "Commissioner of Patents, Washington, D. C."

It is hereby certified that in Letters Patent No. 1,140,635, granted May 25, 1915; upon the application of John M. van Heusen, of Jamaica Plain, Massachusetts, for an improvement in "Rubber Heels," an error appears in the printed specification requiring correction as follows: Page 2, line 16, after the word "function" insert the words *of affording a resilient support to the tread*; and that the said Letters Patent should be read with this correction therein that the same may conform to the record of the case in the Patent Office.

Signed and sealed this 15th day of June, A. D., 1915.

[SEAL.]

J. T. NEWTON,

Acting Commissioner of Patents.
